FIG. 4

TG-7

John J. Ruddick INVENTOR.
BY Davis & Trimble
his ATTORNEYS.

UNITED STATES PATENT OFFICE.

JOHN J. RUDDICK, OF WEST NEWTON, MASSACHUSETTS, ASSIGNOR TO GENERAL STREET SIGNAL CORPORATION, OF ROCHESTER, NEW YORK, A CORPORATION OF NEW YORK.

ELECTRICAL TIME SWITCH.

Application filed February 24, 1922. Serial No. 538,961.

To all whom it may concern:

Be it known that I, JOHN J. RUDDICK, a citizen of the United States, and resident of West Newton, in the county of Middlesex and State of Massachusetts, have invented certain new and useful Improvements in Electrical Time Switches, of which the following is a specification.

The present invention relates to an electrical time switch and more particularly to the type disclosed in an application filed by me on August 2, 1920, Serial No. 400,624 in which a switch is controlled by a detent which in turn is controlled by two motors one of which is in the form of an electro-magnet having an armature movable relatively to the detent but adapted to effect the movement of the detent in both directions. An object of this invention is to provide a construction in which the detent is mounted independently of the armature as by being pivoted on an axis common to an axis about which an armature turns. A further object of the invention is to provide an adjustable connection between the armature and the detent so that the time of the actuation of the detent to open the switch may be varied. Still another object of the invention is to provide an improved motor for moving the armature away from the electro-magnet.

To these and other ends, the invention consists of certain parts and combinations of parts, all of which will be hereinafter described: the novel features being pointed out in the appended claims.

In the drawings:

Fig. 1 is a plan view of a time switch constructed in accordance with this invention;

Fig. 2 shows the time switch in side elevation;

Fig. 3 is a side view showing parts removed to illustrate the motor and its retarding mechanism.

Fig. 4 is an end view with parts removed and broken away;

Fig. 5 is a detail view showing the adjustable connection between the detent and the armature;

Fig. 6 is a detail view of the retarding mechanism; and

Fig. 7 is a detail view showing the connection between the detent and the switch.

Referring more particularly to the drawings, 1 indicates the base on which a brass

base frame 2 is secured, this frame having an upwardly extending portion 3 at one end and two upwardly extending portions 4 at the other end forming a support for a U shape pole piece 5, the arms of which are surrounded by coils 6. These two coils are connected in series, the end of one coil being connected to a binding post 8 while the end of the other coil is connected to an adjustable resistance coil 9 which in turn is connected to a binding post 10.

The electromagnet formed by the two coils 6 with their pole pieces has an armature 11 which, in this instance, is secured to a brass member 12, the latter being pivoted at 13 to the base frame 2. The armature 11 controls the switch. In this instance, the switch embodies two pairs of terminals or contacts 14 pivotally mounted at 15 on anchoring pieces 16 which are secured by screws 17 to a non-conducting slab 18, each contact being acted upon by a spring 19 which yieldingly holds the contacts in a certain position. Binding posts 20 connect with the anchoring plate and lead to any suitable electrical source and apparatus or device. Each pair of contacts 14 is adapted to be connected by connecting members 21, the two members being mounted upon an insulating slab 22 which is secured to a swinging member 23, said swinging member being movably connected at 24 to a brass frame 25 which at one end is secured to the upwardly extending portion 3 of the base frame 2 at 26, and at the other end is secured to the upper end of a post 27, which projects upwardly from the base frame 2 at the opposite end.

The control of the switch may be effected by moving upwardly the swinging member 23 through a detent or operating device actuated by the armature 11. Normally the connecting contacts 21 drop away from the contacts 14 by gravity due to the weight of the arm 23. On the under side of this arm, a roller 28 is arranged for actuation by a detent or operating member 29 the latter being pivoted on the axis 13 common to the turning axis of the armature and having a movement relative to the armature. In this instance, the brass piece 12, on which the armature is mounted, is provided with two stops or abutments 30 and 31, the stop 31 being in the form of a screw adjustable toward and from the stop 110

30. Between these stops the bar 32 on the
detent 29 operates, this bar having at its
upper end a wide bearing surface 33 and
a stop or shoulder 34. When the armature 11
5 is drawn to the pole piece 5, the
stop 30 will cooperate with one side of
the bar 32 and shift the detent so that the
wide bearing surface will act on the roller
28 and move the swinging member 23 up-
10 wardly to connect the contacts 14 by the
connectors 21 as illustrated in Fig. 4. After
the detent has closed the switch, the latter
due to its lost motion connection with the
armature remains in this position until it
15 is moved therefrom by the stop 31, on the
armature-actuated part 12 engaging the
other side of the bar 32 and kicking the
detent from beneath the roller 28 permit-
ing the switch to open. It is apparent that
20 by adjusting the abutment or stop 31, the
time of actuation of the detent to open the
switch may be varied. A screw 35 adjust-
able in the post 27 may have its inner end
adapted to cooperate with the armature
25 actuated part 12 in order to limit the out-
ward movement of the armature with refer-
ence to the electromagnet.

A helical spring 36 is secured at one end
30 to an adjustable screw 37 which is mounted
on an arm 38 secured to the connecting
frame 25 at its lower end. The other end
of the spring 36 is secured at 39 to a
swinging arm 40 which is pivoted at 41 to the
connecting frame 25. The arm 40, through
35 a link 42, connects with a pivoted or motor
member 43 which is secured to a rock shaft
44 journaled in side plates 45 secured by
screws 46 to the opposite sides of the con-
necting member 25. This motor member
40 operates between the coils of the electro-
magnet and connects by a link 46^a with an
arm 47 on the detent 29. It is apparent
that, when the armature 11 is attracted to
the electromagnet, the motor actuated mem-
ber 43 will shift downwardly and store
45 energy in the spring or motor 36, which
will, upon the deenergization of the electro-
magnet, move the armature and the member
12, by which the armature is carried, in
50 the opposite direction.

With the end in view of controlling this
return movement of the armature and its
carrier 12, a timing or retarding mechanism
55 is employed. This consists, in this instance,
of a train of gears embodying a pinion
48 loosely mounted on a shaft 49 and en-
gaged by gear teeth 50 on a motor mem-
ber 43. The pinion 48 has a ratchet wheel
60 51 engaged by a pawl 52 on a gear 53 se-
cured to a shaft 49. The gear 53 meshes
with a pinion 54 on a shaft 55 which also
carries a gear 56, the latter in turn mesh-
ing with a pinion 57 on a shaft 58 which
65 carries an escapement wheel 59. With the
escapement wheel 59 an anchoring device

or pallet 60 cooperates, the latter having a
balancing arm 61 extending transversely of
its shaft 62. It will be seen that this tim-
ing mechanism permits the motor member
43 to move independently thereof when
70 actuated by the armature 11, but when the
motor member is actuated by the spring
36, the timing mechanism comes into action
and retards the return movement of the
motor member 43 under the action of the
75 spring 36.

The operation of the invention will be
understood from the foregoing description
but it may be summarized as follows: When
80 the electromagnet is energized, the arma-
ture 11 is attracted to it and this through
the stop 30 on the armature carrier 12
shifts the detent 29 so that the upper end
of the bar 32 will engage the roller 28
85 and close the switch by elevation of the
member or carrier 23 so that the connectors
21 connect the contacts 14. When the arma-
ture 11 is attracted, the motor member 43
is pulled downwardly through the link 46^a,
90 thus storing energy in the spring 36 so that,
when the electromagnet is deenergized, the
spring 36 starts to move the motor member
43, this being controlled by the timing
mechanism. During the first part of the
95 movement of the motor member 43, the
armature carrier 12 does not shift the de-
tent 29. This shifting only occurs after the
adjustable stop 31 cooperates with the bar
32, so that motion of the motor member
100 43 may be transmitted to the detent. It
is apparent that by adjusting the stop 31
the time in which the actuation of the detent
takes place may be varied.

What I claim as my invention and desire
105 to secure by Letters Patent is:—

1. A time switch comprising switch con-
tacts, an electromagnet having a pivoted
armature, a detent for closing one of the
switch contacts having a movement rela-
tively to the armature and moved by the
armature to close the switch, a swinging
motor member, a link pivotally connected
110 to the swinging motor member and to the
armature for causing the motor member
to be moved in one direction when the arma-
ture is attracted by the electromagnet to
effect the closing of the switch, a spring
for moving said swinging motor member
in the opposite direction, and a retarding
mechanism geared to the teeth of the swing-
ing motor member. 115

2. A time switch comprising switch con-
tacts, an electromagnet having an armature
pivotally mounted, a pair of stops carried
with said pivotally mounted armature, a de-
tent for cooperation with said switch contacts
mounted to turn about an axis common with
the axis of turning of the armature and
moved through one of the stops by the
120 armature to close the switch, and a motor
125

for moving said armature to effect the movement of the detent to open the switch through the other stop.

3. A time switch comprising switch contacts, an electromagnet having an armature, a pivoted carrier on which the armature is mounted provided with a pair of stops and an arm extending therefrom, a detent for effecting the closing of the switch having a movement relatively to the armature and moved by the armature to close the switch, a motor member pivotally mounted and having a link connection with the arm of the armature, and a timing mechanism having a ratchet connection with the motor member.

4. A time switch comprising switch contacts, an electromagnet having an armature, a detent for closing the switch mounted independently of the armature and having a movement relatively to the armature, said detent being moved by the armature to close the switch, a motor for moving said armature to effect the movement of the detent to open the switch, and a timing mechanism having a ratchet connection with the armature to delay the action of the motor to open the switch and permit the electromagnet to move the armature to close the switch without actuating the timing mechanism.

5. A time switch comprising switch contacts, an electromagnet having an armature, a detent for closing the switch having a lost motion connection with the armature and moved by the armature to close the switch, a motor for moving said armature to effect the movement of the detent to open the switch, and an adjustable connection between said armature and the detent for varying the time of the opening movement of the switch.

6. A time switch comprising switch contacts, an electromagnet having an armature pivotally mounted, a pair of stops carried with said pivotally mounted armature, a detent for cooperation with said switch contacts mounted to turn about an axis common with the axis of turning of the armature and moved through one of the stops by the armature to close the switch, and a motor for moving said armature to effect

the movement of the detent to open the switch through the other stop, said last mentioned stop being adjustable.

55

7. A time switch comprising switch contacts, an electromagnet having an armature, a detent for closing the switch having a movement relatively to the armature and moved by the armature to close the switch, an arm extending from the armature, a pivotally mounted motor member having a link connection with said arm, a spring opposing the movement of the motor member by the armature, and timing mechanism connected to the motor member to retard the movement of the latter under the action of the spring.

8. A time switch comprising switch contacts, an electromagnet having an armature and two coils, a detent for closing the switch having a movement relatively to the armature and moved by the armature to close the switch, an arm on the armature extending between the coils, a pivotally mounted motor member arranged to one side of the coils and having a link connection with the arm, a spring opposing the movement of the motor member by the armature, and timing mechanism retarding the movement of the motor member by the spring, said timing mechanism having a ratchet connection with the motor member to permit the movement of the latter by the armature under the action of the electromagnet.

9. A time switch comprising switch contacts, an electromagnet having an armature, a detent for closing the switch having a movement relatively to the armature and moved by the armature to close the switch, a motor member pivotally mounted to one side of the armature and having connection with the armature, a spring opposing the movement of said motor member by the armature, and a timing mechanism for retarding the return movement of the motor member under the action of the spring, said timing mechanism having a clutch connection with the pivotally mounted motor member permitting the movement of the latter in one direction independently of the timing mechanism.

JOHN J. RUDDICK.
